UNITED STATES PATENT OFFICE.

EDWARD M. DEEMS, OF FOREST HILLS, NEW YORK.

RAIL-BOND.

1,333,904.

Specification of Letters Patent. Patented Mar. 16, 1920.

Application filed January 8, 1919. Serial No. 270,149.

To all whom it may concern:

Be it known that I, EDWARD M. DEEMS, a citizen of the United States, and resident of Forest Hills, in the county of Queens and State of New York, have invented certain new and useful Improvements in Rail-Bonds, of which the following is a specification.

This invention relates to improvements in electric bonds for railway rails, and it has for its principal object the provision of a bonding wire bent to standard form and size, and provided with means for holding it in proper shape and sustaining it in the desired position when applied to the rails.

Another object of the invention is to provide a bonding wire of standard form and size, with flexible reinforcing means adapted to bridge the joint between the bonding wire and the bonding pins by means of which the wire is secured to the rails, said flexible means being rigidly connected to the bonding wire.

Another object of the invention is to provide a bonding wire of standard form and size, with a reinforcing means of wire coiled about the horizontal members of the bonding wire in such position as to bridge the joint between the wire and the bonding pins, said coiled wire reinforcing means being extended upwardly and having one end coiled about the main longitudinal strands of the bonding wire, so that said strands will be sustained in an elevated position.

A further object of the invention is to provide a bonding wire with means connected to the entering and supporting ends of the wire and to the main body portion of the wire to sustain the said body portion and maintain it in proper form and prevent it being damaged and broken.

Another object of the invention is to provide a bonding wire of standard form and size and to connect the entering ends of the bonding wire with the body part thereof by a reinforcing and sustaining element, the said reinforcing element forming a permanent part of the bonding element.

There are other important objects and advantages of the invention which will appear hereinafter.

In the drawing, Figure 1 is a side eleva-

tion of a railway rail joint, showing the bonding wire in position;

Fig. 2 a horizontal sectional view; and 55
Fig. 3 a transverse sectional view on the line III—III of Fig. 1.

Referring to the various parts by numerals, 1 designates the rails; 2 the splice bars, and 3 the nuts on the bolts which secure 60 the splice bars to the rail ends. The rail ends are apertured at points beyond the splice bars for the reception of the ends of the bonding wires, and the bonding pins 65 which secure the bonding wires to the rails. 65

The bonding element is formed of two strands of wire bent to form the main upper horizontal portion 4, which, at its ends, is bent downwardly and then carried inwardly to form the inwardly extending lower horizontal portions 5, said inwardly bent portions forming the loops 6. At the inner ends of the horizontal portions 5 the wires are bent at right angles to the vertical plane 70 of the body portion 4 of the bonding element 75 to provide the connecting members 7 which are adapted to be extended through the apertures in the rails. Coiled about the connecting members 7 are the reinforcing elements 8. These elements are formed of a 80 wire coil, and are of sufficient length to cover a substantial portion of the connecting members. One end of the wire forming the reinforcing element 8, preferably that end 85 which is close to the rail web when the device is in position, is extended upwardly and coiled about the main body 4 of the bonding element, as at 9. The coiled reinforcing element 8 is rigidly secured to the connecting members 7 by solder 10, or any other suitable 90 means, said connection being made at a point near the outer ends of the connecting element, as shown clearly at the left-hand end 95 of Fig. 2.

The coils 9 are preferably located on the body portion 4 of the bonding element, at points inward of the ends of the loop 6, that is to say at points inward beyond the sustaining members 7. The said reinforcing and sustaining elements comprising coils 8 100 and 9 and the connecting portion form a bridge between the entering ends and the main body portion, and form a permanent part of the bonding element.

The ends of the connecting elements 7 are first passed through the apertures in the rail ends and are bent over in opposite directions and brought to bear against the surface 5 of the rail web. The bonding pin 11 is then driven into position, the end of said bonding pin entering the reinforcing element 8 thereby expanding the reinforcing element and causing said element and the bonding wires 10 and the bonding pin to be intimately connected. The reinforcing element bridges the joint between the end of the bonding pin and the bonding wires, and forms a resilient reinforcing means at that point. By rigidly and permanently connecting the reinforcing element to the entering members of the bonding wire, the said coiled element will maintain its position on the bonding wire so that the end of the bonding pin may be 20 driven into it. The body part of the bonding wires will be sustained in an elevated position above the nuts 3 and close to the face of the splice-bar, so that the nuts may be manipulated in the usual way without damage to the bonding wires. The coil 9 25 forms a resilient support for the main body part of the bonding element and sustains it out of contact with the ground and above the railway ties on which the tracks are supported.

Coiled, flexible reinforcements 8 take up the vibrations in the bonding wires and prevent the breaking of the bonding wires at points adjacent the ends of the bonding pins, 35 and at the same time securely hold the bonding wires in close engagement with the bonding pins. These reinforcing elements also serve as a means for increasing the electrical contact between the bonding wires and the bonding pin. The reinforcing supporting coils 9 hold the main portions of the bonding element in intimate contact with each other, while at the same time permitting the wires to respond to the vertical vibrations of the rails.

What I claim is:

1. A rail bond comprising an arched bridging element formed of two strands of wire and having laterally bent rail-entering 50 end portions, and a pair of bracing members extending downwardly and laterally from the raised portion of the bridging element to the laterally bent rail-entering portions of said element and connected at both ends 55 with the two strands of said element.

2. A rail bond comprising an arched bridging element formed of two strands of wire arranged side by side and having laterally bent rail-entering end portions, means 60 for holding the two strands of each rail-entering end portion spaced apart to receive a bonding pin, and a pair of bracing elements extending between the rail-entering end portions and the raised portion of the

bridging element and bent at their ends 65 around both strands of the element to prevent separation of the strands.

3. A bonding element for railway rails formed with a body portion and laterally extending entering ends, and coiled wire reinforcing elements rigidly connected to the entering ends and adapted to receive and grip the ends of bonding pins, one end of the wire of the reinforcing element being extended upwardly and coiled about the 75 body portion of the bonding element to form a supporting means therefor.

4. A bonding element for bonding railway rails formed of a pair of wires bent to 80 form a main body portion and laterally extending entering ends adapted to be passed through apertures in the webs of the railway rails, and a coiled wire reinforcing element rigidly connected to and surrounding 85 the entering ends and adapted to receive and be expanded by bonding pins, one end of the wire of the reinforcing element being extended upwardly and outwardly and coiled about the body portion of the bonding element to form a supporting means therefor. 90

5. A bonding element for bonding railway rails formed of a pair of wires bent to 95 form a main body portion and laterally extending entering ends adapted to be passed through apertures in the webs of the railway rails, a coiled wire reinforcing element surrounding the entering ends and adapted to receive and be expanded by bonding pins, one end of the wire of the reinforcing element being extended upwardly and coiled about the body portion of the bonding element to form a supporting means therefor, and means rigidly connecting the reinforcing element to the bonding wires. 100

6. The combination of two rails arranged 105 end to end and having transverse apertures therein, a bonding wire having end portions bent downwardly and inwardly, the ends of said downwardly and inwardly bent portions being bent laterally and extending through the apertures in the rails, bonding pins extending through the apertures in the rails, and a pair of reinforcing and vibration-dampening devices each having a sleeve-like portion at its lower end frictionally embracing one bonding pin and engaging the adjacent laterally bent end of the bonding wire beyond the end of the pin, the upper ends of said devices being connected with 110 the bonding wire. 115

7. The combination of two rails arranged 120 end to end and having apertures there-through, a bonding element having its ends bent downwardly and laterally and extending through the apertures in the rails, a pair of bonding pins extending through 125 said apertures, and a pair of reinforcing elements each having a coiled lower end em-

bracing the end of one bonding pin and the adjacent laterally bent end of the bonding element, the body portion of each reinforcing element extending upwardly from the 5 innermost convolution of the coiled lower end and being bent around the bonding element at its upper end.

8. A bonding element for railway rails formed with a body portion and laterally 10 extending entering ends and provided with

reinforcing means coiled around the entering ends and adapted to receive and grip the ends of bonding pins, the reinforcing means being extended upwardly and coiled about the body portion of the bonding ele- 15

ment to form a supporting means therefor.

In testimony whereof I hereunto affix my signature.

EDWARD M. DEEMS.
